CALKING MACHINE

Filed Dec. 22, 1923

UNITED STATES PATENT OFFICE.

HOWARD ASHLEY PEDRICK, OF BALA, PENNSYLVANIA, ASSIGNOR TO EV-AIR-TIGHT CALKING CO., OF PHILADELPHIA, PENNSYLVANIA, A CORPORATION OF DELAWARE.

CALKING MACHINE.

Application filed December 22, 1923, Serial No. 682,174, and in Canada February 12, 1923.

My invention relates to apparatus for extruding highly viscous or plastic calking materials of the nature of putty or the like, in a relatively small stream for the purpose of closing joints and cracks in and between the masonry, stonework, and other parts of building construction, familiarly known as a "calking gun" and this application is a continuation in part of my copending application, Serial No. 612,108, filed Jan. 11, 1923.

One object of my invention is to provide a relatively small, and easily operated "gun" for containing the calking material, and from which it may be forcibly discharged under the influence of a suitable fluid under pressure.

A further object of my invention is to provide a structure adapted to utilize compressed air for the expulsion of the contained calking material, and so constructed as to insure the complete or substantially complete delivery of each charge, as well as to facilitate recharging; the parts being conveniently arranged to permit rapid refilling and closure.

A further object of my invention is to provide a novel form of container substantially spherical in shape, having a flexible diaphragm disposed within the same and dividing the interior into a pair of chambers whose dimensions will vary depending upon the position of the diaphragm; one chamber receiving the body of calking material to be subsequently discharged and the other chamber receiving fluid under pressure to act upon such diaphragm and effect discharge of such calking material.

A further object of my invention is to provide means for preventing injury to or destruction of the flexible diaphragm after it has effected displacement of the calking material and before the supply of air pressure has been cut off, and a still further object of my invention is to provide the central portion of said diaphragm with a metal guard to prevent its entrance into the discharge or outlet passage by the action of the fluid pressure medium after the plastic calking material has been displaced; thereby avoiding injury to or destruction of the diaphragm.

I attain these objects and other advantageous ends, all of which are more fully set forth hereinafter, by the mechanism illus-

trated in the accompanying drawings, in which:

Figure 1, is a perspective view of a "calking gun" embodying my invention.

Fig. 2, is a sectional elevation on the line II—II, Fig. 1.

Fig. 3, is a cross sectional view on the line III—III, Fig. 2, looking in the direction of the arrows.

Figs. 4 and 5, are detached sectional views illustrating modified details of construction within the scope of my invention, and

Figs. 6, 7 and 8, are sectional views of the pressure controlling valve which I may employ.

In the drawings herewith, the body of my improved "calking gun" is shown as made up of a pair of cup-shaped, substantially hemi-spherical shells, 1 and 1^a, having meeting flanges 2 and 2^a, secured together by screw bolts 3, and nuts 4. A flexible diaphragm 5 is disposed within the chamber formed by said shells, and this diaphragm may be secured between the flanges 2 and 2^a. In the preferred embodiment of my invention, this diaphragm is of resilient material such as sheet rubber, and with its marginal edge clamped between the flanges 2 and 2^a, a fluid tight joint is provided. The diaphragm may be slightly greater in extent than the cross sectional area of the internal chamber so that normally it lies within the same, clear of the walls, as illustrated in Fig. 1.

This diaphragm serves to divide the interior of the chamber formed by the shells 1 and 1^a, into a pair of compartments 6 and 7; the larger one 7, as defined by the inner wall of the shell 1^a and the diaphragm when the latter is in the position shown by full lines, Fig. 1, serving to receive calking material which is subsequently ejected from the device through a discharge outlet 8, to which a nozzle 9, may be attached, while the other chamber, indicated at 6, is in communication with a source of fluid under pressure, compressed air for instance, which may act upon the diaphragm and cause it to expand against the body of calking material in the chamber 7 and force it therefrom.

For convenience, the shell 1 will be referred to as the head of the device, and this head is provided with a suitable inlet passage 10 for the introduction of fluid under pres-

sure, compressed air for instance, from any suitable source, which may enter via a pipe 11, tapped into a boss 12 in which such inlet passage 10 may be formed. The head is provided with a handle, which may comprise a tubular shell 13, having a post 14 at one end, whereby it may be secured to said head; said post having an end 14^a in threaded engagement with a boss 12^a carried by the shell 1.

10 As a convenient means of securing the opposite end of the handle in place, the pipe 11 conveying the fluid pressure may pass through the shell of the handle and be in threaded engagement with the latter.

15 The pipe 11 is provided with a valve 15 of the three-way type, whose plug 16 may be provided with a through passage 17 which may be placed in communication with the inlet passage 10 and the air supply pipe 11, 20 as shown in Fig. 6, and with a passage 17^a whereby the chamber 6 may be placed in communication with an exhaust port 18 in the valve shell, as shown in Fig. 7, at will. With such an arrangement, air under pressure 25 may be delivered to the chamber 6 from said conduit 11, or exhausted from the chamber 6, as may be desired. Additionally, the exhaust port 18 may be employed for another important function, to wit; by placing 30 the supply pipe 11 leading from the source of pressure in communication with such port 18, as indicated in Fig. 8, fluid pressure discharged therefrom, air for instance, may be employed to cleanse from the crack or joint 35 to be calked, any collected dust, dirt or chips, that would interfere with its proper calking. In the sectional views Figs. 6, 7 and 8, the source of pressure enters the pipe 11 from the right, passes through the valve to the extension of pipe 11 and enters the chamber 6 via the inlet 10; Fig. 6, showing the position of the valve when air pressure is discharging into said chamber 6; Fig. 7, showing the position of the valve when air pressure in 45 the chamber 6 is passing to exhaust, and Fig. 8, showing the position of the valve when the air pressure is employed for the purpose of cleaning dust and dirt from the cracks or crannies to be calked.

50 The shell 1^a has an opening 20 through which calking material may be introduced into the chamber 7 of the structure; normally closed by a cap 21 threaded therein. This cap has the relatively small outlet 8 for 55 the material to be ejected, and such cap may be flanged to extend over the end of the wall surrounding said opening 20. In practice, it is desirable that the structure shall be as light as possible, and to that end, the shell 60 may be made of aluminum. As there is a tendency of this material to stretch, the wall of the opening 20 is preferably provided with a band 22 of spring steel or other suitable material, to reinforce the same.

65 It has been found in practice that a plain

diaphragm will be forced into the outlet opening 8 of the shell 1^a after the material has been discharged, and there is danger of rupturing the diaphragm at this point. To prevent this, I provide the diaphragm, centrally of its body, with a metal guard designed to bridge the outlet opening 8 and prevent said diaphragm being forced therein. This guard may be in the form of a pair of plates so formed and of such dimensions 70 as to constitute a rigid support for the central portion of the diaphragm that is brought adjacent to the entrance of the outlet 8 under the action of the fluid pressure, so as to effectually prevent said diaphragm being 75 forced into said opening or being abnormally stressed or ruptured by the action of the air tending to force it therein. These plates may be substantially flat, or they may be concavo-convex and disposed in either of 80 the positions illustrated in the drawings. In accordance with this feature of my invention, the central part of the diaphragm 11 carries reinforcing elements in the form of plates 25 and 25^a applied to the opposite 85 faces of the same, and rigidly clamped thereto by suitable fastening means, which may be in the form of a screw bolt 27 and nut 28. When the chamber 7 is empty and the valve 15 is in position to exhaust the air 90 from the chamber 6, the diaphragm tends to assume the position shown by full lines, Fig. 2, so that when the cap closure 21 is detached, calking material may be introduced into said chamber 7; substantially 100 filling the same, after which the cap closure 21 may be secured in place. Upon proper operation of the valve 15, air under pressure will be delivered to the chamber 6, and acting upon the diaphragm will cause it to expand and compress the body of material in the chamber 7 of the section 1^a; causing this material to be discharged through the outlet 8, and through the nozzle or delivery tube 9, 105 when the latter is employed. As the diaphragm will be distended by the pressure and caused to follow the contour of the wall of the section 1^a, all or substantially all of the material within the chamber 7 and adhering to said wall will be forced out. 110

The rate of delivery of the material may be regulated by the position of the valve 15 and when the plastic material has been discharged from the chamber 7, the diaphragm will assume the position shown by broken 115 lines in Fig. 2, with the reinforcing plates seated over the entrance to the outlet opening 8; preventing further movement of the diaphragm and avoiding all danger of the fluid pressure puncturing the same by blowing a portion into said outlet passage. After the pressure has been cut off and the valve turned to the position indicated in Fig. 7, to exhaust the air from the chamber 6, the diaphragm will tend to return to the 120 125 130 plain

position shown by full lines, Fig. 2, and after this, the cap closure 21 may be removed and a new charge of clinking material introduced into said chamber 7. By the use of the reinforcing plates 25 and 25^a, the life of the diaphragm is indefinitely prolonged.

I claim:

1. In a calking device, the combination of a casing comprising a pair of hemi-spherical sections separable upon a substantially equatorial line; one of said sections having an inlet for fluid under pressure and forming a head for said casing and the other having an outlet passage, a discharge nozzle connected to said latter section in line with said outlet passage, a reinforced flexible diaphragm disposed within the chamber of said casing and confined between the sections of the same, and means for controlling the flow of fluid pressure to the chamber defined by the wall of said head and the diaphragm for causing the latter to act upon and expel material from the casing through the discharge nozzle.
2. In a calking device, the combination of a spherical casing having an inlet passage and an outlet passage, a centrally reinforced rubber diaphragm dividing said casing into a pair of chambers; one of said chambers having the inlet passage and being in communication with a source of fluid under pressure, and the other chamber having the outlet passage and receiving a body of viscous calking material to be subsequently delivered therefrom, a discharge nozzle connected to said casing in line with said outlet passage, and means for controlling the inlet of said fluid pressure whereby it may act upon said diaphragm and cause the latter to expand and expel the material from said second chamber through said discharge nozzle.

3. In a calking device, the combination of a spherical casing comprising a pair of flanged sections detachably connected together, one of said sections having an inlet passage and the other section having an outlet passage, a discharge nozzle carried by said section in line with said outlet passage, a centrally reinforced rubber diaphragm internally disposed; said diaphragm having its edge confined between said flanged sections and dividing said casing into a pair of chambers and the chamber having the outlet passage receiving a body of viscous calking material to be subsequently delivered through said discharge nozzle, a cover plate therefor in which the outlet passage is formed and to which said discharge nozzle is connected; the chamber having the inlet passage being in communication with a source of fluid under pressure, and means for controlling the inlet of said fluid pressure whereby it may act upon said diaphragm and cause it to expand and expel

the material from the other chamber through 65 said discharge nozzle.

4. In a calking device, the combination of a spherical casing made in separable sections and having an inlet passage and an outlet passage, a discharge nozzle secured in 70 said outlet passage, a reinforced rubber diaphragm internally disposed and dividing said casing into a pair of chambers; one of said chambers having the inlet passage and the other chamber having the outlet passage, a detachable cover member for the section of said casing in which said outlet passage is formed, a reinforcing band for the casing wall having the opening receiving said cover member; the chamber having the 80 inlet passage being in communication with a source of fluid under pressure, and means for controlling the inlet of said fluid pressure whereby it may act upon said diaphragm and cause it to expand and expel the 85 material from the other chamber through said discharge nozzle.

5. In a calking device, the combination of a spherical casing made in separable sections and having an inlet passage for fluid pressure and an outlet passage for calking material, a discharge nozzle secured in said outlet passage, a reinforced rubber diaphragm internally disposed between said sections and dividing said casing into a pair 95 of chambers; one of said chambers having the inlet passage and the other chamber having the outlet passage, a detachable cover member for the casing in which said outlet passage is formed; said cover member closing an opening through which calking material may be introduced and said diaphragm lying normally out of contact with the walls of said casing; the chamber having the inlet passage being in communication with a 100 source of fluid under pressure, and means for controlling the inlet of said fluid pressure whereby it may act upon said diaphragm and cause it to expand and expel the material from the other chamber through said 110 discharge nozzle.

6. A calking device comprising a hollow body, a flexible diaphragm mounted within said body and dividing the interior thereof in two chambers; one of which chambers receives calking material and is provided with an outlet opening, a source of fluid pressure communicating with the other chamber, and rigid reinforcing means for said diaphragm; said reinforcing means being positioned to 115 prevent the diaphragm being forced into the outlet opening by the action of the fluid pressure.

7. A calking device comprising a hollow body formed of two hemi-spherical sections 125 detachably secured together, a flexible diaphragm clamped between said sections and dividing the body into two independent

chambers, an outlet opening leading from one of said chambers, an inlet opening communicating with the other chamber and connected to a source of air under pressure, and a reinforcing plate secured to the central portion of the diaphragm in position to seat over the outlet opening when the diaphragm has been moved toward the same by the action of the fluid pressure.

10 8. A calking device comprising a pair of hollow flanged sections hemi-spherical in shape, a flexible diaphragm clamped between the flanges of said sections; one of said sections having an outlet opening and 15 the other section having an inlet opening with an air supply conduit connected thereto, and a pair of concavo-convex metal plates centrally clamped to opposite faces of the diaphragm in position to seat over the 20 outlet opening when the diaphragm has been moved toward the latter by the action of the fluid pressure.

9. In a calking device, the combination of a casing comprising a pair of sections of substantially the same size detachably connected together; one of said sections having an outlet passage and the other section having an inlet for fluid under pressure, a discharge nozzle secured in said outlet passage,

30 a reinforced flexible diaphragm disposed within the chamber of said casing and confined between the sections of the same and limited in such area as to lie in its normal position clear of the walls of the chamber, and means for controlling the flow of fluid pressure to act upon said diaphragm and cause the latter to expel material from the casing through said discharge nozzle.

10. In a calking device, the combination of a casing comprising a pair of sections of substantially the same size detachably connected together, one of said sections having an outlet passage and the other section

40 having an inlet for fluid under pressure, a flexible diaphragm disposed within the chamber of said casing and confined between the sections of the same, a reinforcing band for the casing wall having the outlet passage, and means for controlling the flow of fluid pressure to the casing for causing the same to act upon the diaphragm and expel material from the casing.

11. A calking device consisting of a hollow body; a flexible diaphragm mounted in said body to divide the interior thereof into two chambers, of which one has an outlet opening; a source of fluid under pressure connected to the other chamber; and a rigid reinforcing device for the diaphragm positioned to prevent its being forced into the outlet opening by the action of the air under pressure.

12. A calking device consisting of a hollow body formed with two sections; a flexible diaphragm clamped between said sec-

tions and dividing the body into two chambers; a nozzle having an outlet opening from one of said chambers; a source of air under pressure connected to the other chamber; and a reinforcing plate mounted on the central portion of the diaphragm; said plate being adapted to seat over said outlet opening.

13. A calking device consisting of two hollow sections; a flexible diaphragm clamped between said sections; an outlet nozzle for one of the sections; an air supply conduit connected to the other section; and a pair of parallel concave metal plates centrally clamped to opposite faces of the diaphragm in position to seat over the outlet opening when the diaphragm has been moved toward the same by the action of air under pressure.

14. A calking device comprising two hollow sections; a flexible diaphragm clamped between said sections; one of said sections having an outlet opening and the other of said sections having an inlet opening; a delivery pipe associated with said outlet opening and having a flared outer end portion; and a reinforcing plate mounted on said diaphragm, said plate being adapted under the action of air under pressure to seat over said outlet opening.

15. A calking device comprising two hollow sections; a flexible diaphragm clamped between said sections; one of said sections being provided with a perforated boss; an air supply conduit operably associated with said perforated boss; the other of said sections being provided with a projecting flange; an outlet pipe extending from said projecting flange; and a rigid reinforcing device for the diaphragm so positioned as to prevent the same being forced into said outlet opening by the action of air under pressure.

16. In a calking device, the combination of a pair of hemispherical sections detachably connected together on an equatorial line and forming a hollow casing, an inlet for fluid under pressure connected to one of said sections, a discharge nozzle connected to the other section, a flexible diaphragm of concavo-convex form disposed within the chamber formed by said sections and confined between the latter with its greatest area normally out of contact with the walls of said casing, and means for controlling the flow of fluid pressure to the chamber defined by the wall of one section and said diaphragm for causing the latter to act upon and expel material through the nozzle carried by the other section.

17. In a calking device, the combination of a casing comprising a pair of hemispherical sections of substantially the same size detachably connected together, an outlet passage carried by one of said sections, an inlet for fluid under pressure carried by the

other section, a discharge nozzle secured in said outlet passage, a reinforced flexible diaphragm of concavo-convex form disposed within the chamber of said casing and confined between the sections of the same; said diaphragm dividing said chamber into two compartments and being limited in such area as to have a normal position clear of the walls of the chamber, and means for control-

ling the flow of fluid pressure into one of 10 said compartments to act upon said diaphragm and cause the latter to expel material from the other compartment through said discharge nozzle.

In witness whereof I have signed this 15 specification.

HOWARD ASHLEY PEDRICK.
